LABORATORY CABINET

Robert M. Courtwright, Box 1261, Tacoma, Wash.

Filed Jan. 23, 1962, Ser. No. 68,479

Term of patent 14 years

(Cl. D16—2)

FIG. 1

FIG. 2

FIG. 3

FIG. 4

FIG. 1 is a perspective view illustrating a laboratory cabinet embodying my new design.

FIG. 2 is a side elevation view thereof.

FIG. 3 is a plan view thereof.

FIG. 4 is a front elevation view thereof.

The side of the cabinet not shown is a mirror image of that illustrated in FIG. 2.

I claim:

The ornamental design for a laboratory cabinet, as shown and described.
